UNITED STATES PATENT OFFICE.

RUSSELL C. JONES, OF BRONXVILLE, NEW YORK, ASSIGNOR TO THE GRISCOM-RUSSELL COMPANY, OF NEW YORK, N. Y., A CORPORATION OF DELAWARE.

SUBMERGED DRAIN COOLER IN EVAPORATORS.

Application filed July 24, 1924. Serial No. 728,039.

The present invention relates to steam generating systems and has to do particularly with the construction and operation of evaporators in a steam generating system 5 with particular reference to the disposition of the hot drains from the heating coils of the evaporators so that the available heat in such drains may be advantageously used in the system.

10 Raw water ordinarily available for use in steam generating plants contains undesirable impurities to such an extent that the water must be treated to remove such impurities before it can be successfully used 15 in the boilers. For this reason the impure raw water is usually distilled in evaporators provided for the purpose and the purified output employed as the boiler feed water.

20 The heat for effecting the evaporation of the impure raw water is commonly derived from steam drawn from the boilers and condensed in the heating element of the evaporator as heating medium therefor. The purified vapor output of the evaporator is 25 drawn off and condensed, and the condensate is then passed on to the boiler to supply the necessary makeup requisite to the operation of the system. When the requirements of the system demand that more than one evaporator be employed, it is common practice 30 to install two or more evaporators as needed, to arrange for supplying heating steam to the first evaporator directly from the boilers, and to utilize as heating medium for 35 each succeeding evaporator, the vapor output of the preceding unit.

The available heat contained in the evaporator vapor output and in the hot drains issuing from the heating elements of the 40 evaporator units must be utilized in the system in order to avoid heat losses. The heat is usually conserved by passing these hot returns into heat exchanging relation with the boiler feed water, and thus preheating 45 the water before its admission to the boilers. The evaporator coil drains are commonly discharged from the evaporating unit at a relatively high pressure and thus represent a considerable amount of available heat. In 50 order to effect discharge of condensate from the evaporator heating elements, a trap is provided in conjunction with each heating element and functions to permit discharge of condensate from the element and at the 55 same time to prevent escape of uncondensed

heating steam. If the evaporator vapor output and the drains from the heating elements are passed into the boiler feed open heater, the amount of heat contained in these returns is commonly in excess of that which 60 can be accommodated in the open heater and consequently the water in the heater will be raised to the boiling point and a loss of steam will result. To avoid this difficulty, it has been proposed to transfer a portion 65 of the heat from these relatively high temperature returns, to the boiler feed water in auxiliary heaters maintained at pressures considerably above atmospheric.

In a system employing more than one 70 evaporator, it has also been proposed to discharge the coil drains from the evaporators into a region of reduced pressure corresponding to the pressure of the vapor discharged from the last effect evaporator, whereupon the excess of sensible heat in the 75 coil drains corresponding to the pressure existing in the coils over that corresponding to the pressure into which the coil drains are discharged, will produce a vaporizing or flashing action and will thus convert a portion 80 of the discharged condensate into steam. Coil drains from an evaporator may also be reduced to the pressure of the vapor output of that evaporator, and the quantity of 85 resulting flash steam may be joined with the vapor output and used as heating medium for the succeeding evaporator. These arrangements are open to the objection of high initial cost of installation, difficulties 90 of operation and regulation due to an increased number of operating units, and the like.

It has also been proposed to condense the coil drains from the heating elements of the evaporators in the boiler feed heater without the intermediate use of a trap, the object of this arrangement being to eliminate the problem of operating and regulating the trap. In these installations, the heat exchanger which receives the coil 95 drains must be of ample capacity to insure complete condensation of all steam admitted to it in order to prevent heat loss by steam blowing thru the heat exchanger unden- 100 densed.

It is a principal object of this invention to provide an evaporator system which effects the disposition of the drains from the heating elements of the respective evaporator units and the utilization of the available 110

heat in these drains in a simple and convenient manner and in such fashion as to secure maximum efficiency from the evaporating apparatus with a minimum difficulty 5 in operation; such as, for instance, in the regulation of traps and the like. To accomplish this object, the invention contemplates absorbing a certain amount of the available heat contained in the hot drains 10 issuing from the evaporator elements by passing such drains into heat exchanging relation with the fluid in the evaporating space of the respective evaporator units. The coil drains from each evaporator unit 15 are passed into heat transferring relation with the liquid undergoing evaporation in that unit. The invention further contemplates passing the coil drains from each evaporator unit into heat exchanging relation, not only with the liquid undergoing 20 treatment in that unit, but also with the liquid being evaporated in succeeding units operating at successively lower pressures. In this way, the available heat in the drains 25 from each evaporator unit is abstracted in a succession of steps at decreasing pressures and temperatures. A trap is preferably provided in connection with the heating element of each unit to prevent passage of 30 uncondensed heating steam thru the elements.

It is also an object of the invention to provide for the heat transfer between the coil drains and the liquid undergoing treatment 35 by means of a rugged, inexpensive heat exchanger contained entirely within the evaporator unit itself and also designed to facilitate removal of scale which may accumulate upon the heat transferring surfaces of 40 the unit. These heat exchangers for accommodating the coil drains are so arranged in reference to the principal heating elements of the evaporator units that they may be treated for the removal of scale deposits at 45 the same time and by the same operation by which removal of scale from the main heating elements is accomplished.

I have illustrated a preferred embodiment 50 of my invention in the accompanying drawings, in which Figure 1 is an elevational view showing an evaporator embodying my invention; Figure 2 is an elevational view showing a system embodying my invention wherein two evaporating effects are employed; and Figure 3 is a similar elevational view showing a modification.

The evaporator consists of a shell 1 for containing the liquid under treatment and a suitable heating element 2 disposed within 60 the shell 1 for the purpose of effecting vaporization of the liquid in the shell. The heating element 2 commonly consists of a suitable arrangement of heat transferring tubing submerged in the liquid in the shell 65 1 and receiving thru line 3 a supply of heat-

ing steam from the main boilers or from another suitable source. The heating element 2 here shown consists of a plurality of vertically disposed helical coils extending between inlet manifolds 4 provided for the purpose of distributing the incoming steam to the respective coils, and discharge manifolds 5 provided for the purpose of receiving the fluid discharged from the coils and passing it out of the apparatus. A trap 6 is 70 connected to the discharge manifolds 5 and serves to permit discharge of condensate from the heating element and at the same time to prevent discharge of uncondensed steam. The vapor arising from the liquid 75 in the shell 1 passes up thru the steam dome 7 of the evaporator and is discharged thru the vapor outlet line 8, whence it is disposed of as desired. The vapor output is commonly passed into heat exchanging relation 80 with the boiler feed water in order to preheat the water before its admission to the boilers.

The invention contemplates transfer of 85 heat from the condensate discharged from the heating element 2 to the water within the shell 1. To this end, a heat exchanger 9 is built into the evaporator shell 1 at a point near the bottom of the shell. The condensate passing the trap 6 is conveyed directly 90 into the heat exchanger 9 which may be at any desired pressure lower than that in coil 2, and during the passage of the condensate thru this heat exchanger ample opportunity is afforded for transfer of heat to the liquid in the shell 1. In order to prolong the length of time during which the heat transfer from the condensate to the liquid within the shell takes place, the heat exchanger 9 is divided by means of partitions 10 and 11 into three passes so that the condensate will traverse the length of the heater three times before it is finally discharged thru line 12 and passed into heat 100 transferring relation with the boiler feed water, or is otherwise disposed of. These partitions are arranged in headers 13 and 14 provided at the respective ends of the tubes constituting the heat exchanger. During 105 this prolonged period of heat transfer, the temperature of the coil drains passing the trap 6 will be reduced to substantially the temperature of the liquid under treatment in shell 1, with the result that a considerable economy in operation is effected.

The liquid being evaporated may contain 110 a considerable amount of scale forming impurities and the invention contemplates construction of the heat exchanger 9 in such fashion that scale accumulating on the heat transferring surfaces may readily be removed. To this end, the headers 13 and 14 are rigidly secured to the evaporator shell 1 and are thus maintained at a fixed distance 115 apart. The heat transferring tubes of the 120

heat exchanger 9 are rigidly secured at their respective ends in the headers 13 and 14 and are slightly bowed, so that upon changes in temperature with resulting longitudinal expansion or contraction of the tubes, the amount which they are bowed will vary, and thereby cause a flexure of the tubes which will effectively loosen and crack off accumulated scale deposits. The requisite

change in temperature for effecting scale removal is produced by passing hot water and cold water successively thru the heat transferring tubes. The heat exchanger 9 is connected in series relation with the main heating element 2 of the evaporator and, since the heating element 2 is usually arranged for accomplishing scale removal by subjecting the element to abrupt temperature changes, scale removal from both the heating element 2 and the heat exchanger 9 may be effected at a single operation by passing hot and cold fluid successively thru the respective heat exchangers in series arrangement.

The present invention is applicable equally well to a system employing a single evaporating unit or effect and to a system employing more than one unit. A system employing two evaporating units is shown in Figure 2. Vapor from the first effect evaporator is passed thru line 8 into the heating element 2^a of the second effect and serves as heating medium for effecting evaporation in the second evaporator 1^a. A heat exchanger 9^a and trap 6^a are provided for handling drains from the heating element 2^a of the second effect and transferring heat from such drains to the water in shell 1^a. The discharge line 12 conveying the drains issuing from the heat exchanger 9 is joined with the discharge from the trap 6^a of the second effect evaporator and the heat exchanger 9^a therefore receives not only the coil drains from the heating element 2^a but also the drains issuing from the heating element 2 of the first effect evaporator. In this fashion, the drains from the first effect are passed successively into heat transferring relation with the liquid undergoing evaporation in the first effect and the liquid undergoing evaporation in the second effect. If more than two evaporating units are employed, this system is carried out so that the coil drains from each effect are first passed into heat exchanging relation with the liquid undergoing evaporation in that effect and are then successively passed into heat transferring relation with the liquid undergoing evaporation in each of the succeeding effects.

In Figure 3 I have illustrated an arrangement in which the auxiliary heat exchanger 9 is positioned vertically in the evaporator shell. This arrangement may be of advantage in certain installations and particularly results in placing the heat ex-

changer 9 in such position that it will not receive scale which is cracked off the main heating element 2 of the evaporator, as is the case when the heat exchanger 9 is located in the bottom of the evaporator shell. A discharge line from the trap 6 is passed into the upper end of the heat exchanger 9, the excess pressure in the coils 2 being ample to produce the flow from the trap into the heat exchanger 9.

While I have herein illustrated only preferred embodiments of my invention, certain changes and modifications in construction and arrangement may be made within the scope of the appended claims.

I claim:

1. In a steam generating system, a series of evaporators, each evaporator having a closed heating element therein, said evaporators being operable at successively lower pressures for supplying purified water vapor, means for supplying steam at relatively high pressure to the heating element of the first evaporator of the series, means for passing the drains from said heating element into heat exchanging relation with the liquid in the evaporating space of that evaporator, and means for passing said drains into heat exchanging relation with the liquid in the evaporator space of the next evaporator operable at lower pressure.

2. In a steam generating system, a series of evaporators, each of said evaporators having a closed heating element therein, said evaporators being operable at successively lower pressures for supplying purified water vapor, means for supplying steam to the heating element of the first of said evaporators, means for passing the drains from said heating element into heat exchanging relation with the liquid under treatment in that evaporator, and means for passing said drains into heat exchanging relation with the liquid in the evaporating space of the succeeding evaporator operable at a lower pressure.

3. In a steam generating system, a series of evaporators, each of said evaporators having a closed heating element therein, said evaporators supplying purified water vapor, means for supplying steam to the heating element of the first evaporator, means for supplying to each succeeding evaporator as heating medium therefor the vapor output of the preceding evaporator, and means for passing the drains from each evaporator into heat exchanging relation with the liquid being evaporated therein.

4. In a steam generating system, a series of evaporators, each of said evaporators having a closed heating element therein, said evaporators supplying purified water vapor, means for supplying steam to the heating element of the first evaporator, means for supplying to each succeeding evaporator as

- heating medium therefor the vapor output of the preceding evaporator, means for passing the drains from each evaporator into heat exchanging relation with the liquid being evaporated therein, and means for passing the drains from each evaporator into heat exchanging relation with the liquid being evaporated in each succeeding evaporator.
10. 5. In a steam generating system, a series of evaporators, each of said evaporators having a closed heating element therein, said evaporators supplying purified water vapor, means for supplying steam to the heating element of the first evaporator, means for supplying to each succeeding evaporator as heating medium therefor vapor from the preceding evaporator, means for passing the drains from each evaporator into heat ex-
15 changing relation with the liquid being evaporated therein, and means for joining the drains from each evaporator heating element with the condensate from the preceding elements and passing said joined fluids into heat exchanging relation with the fluid in the evaporating space of said evaporator.
6. An evaporator comprising a shell for containing liquid under treatment, a closed heating element in said shell for conducting steam into heat transferring relation with said liquid to effect vaporization thereof, a trap for receiving the drains discharged from the heating element and preventing escape of uncondensed steam, and a heat exchanger within said shell for receiving the fluid issuing from said trap and transferring heat therefrom to the liquid under treatment, said heat exchanger comprising
- 30 a plurality of longitudinally flexible tubes having fixed ends, whereby changes of con-
- 25
- 35
- 40

formation upon changes in temperature thereby exfoliate accumulated scale.

7. An evaporator comprising a shell for containing the liquid under treatment, a closed heating element in said shell for conducting steam into heat transferring relation with said liquid to effect vaporization thereof, a trap for receiving the drains discharged from the heating element and preventing escape of uncondensed steam, and a heat exchanger within said shell for receiving the fluid issuing from said trap and transferring heat therefrom to the liquid under treatment, said heat exchanger comprising a plurality of slightly bowed tubes having rigid end supports whereby the curvature of said tubes will vary upon changes in temperature to thereby exfoliate accumulated scale.

8. In a steam generating system, a series of evaporators operable at successively lower pressures, each of said evaporators having a closed heating element therein, said evaporators supplying purified water vapor, means for supplying steam at relatively high pressure to the heating element of the first evaporator, means for withdrawing the drains from said heating element and reducing the pressure thereon, means for passing said drains into heat exchanging relation with the liquid undergoing treatment in said evaporator, means for joining said drains at said reduced pressure with the coil drains from a succeeding evaporator, and means for passing said joined drains into heat exchanging relation with the liquid undergoing treatment in the evaporators operable at pressures lower than that at the first evaporator.

In testimony whereof I affix my signature.
RUSSELL C. JONES.
